UNITED STATES PATENT OFFICE.

ALBERT WEDDELL AND WILLIAM THOMAS TOLHURST, OF TIPTON, ENGLAND.

PIT TUB, WAGON, AND THE LIKE.

Application filed October 2, 1926, Serial No. 139,215, and in Great Britain October 27, 1925.

The invention relates to pit tubs and wagons and the like, and distinctly to the construction of the bodies thereof, and provides the hereinafter described and claimed 5 improvements therein.

The body of such a vehicle is sometimes built up of a separately constructed bottom, separately constructed opposite sides, and separately constructed opposite ends, rigidly 10 riveted together. There are two types of body generally in use, the one known as flat bottomed, which is usually mounted upon a separate under-frame, and the other known as well-bottomed, and having applied to its 15 ends buffer beams.

According to the invention the boundary edge of the bottom is turned upwardly and inwardly to form all round said bottom an upper and inner hook edge of substantially 20 **U** cross-section. The lower horizontal edges of the opposite sides and ends are also formed with outwardly turned hook sections to engage the hook formations of the bottom by horizontal movement outwardly. The 25 vertical edges of the rigidly built sides and ends also have corresponding hook formations adapted to be put into engagement by a horizontal movement outwardly, that is to say, the vertical edges of the ends for their 30 full depth have hook formations to engage corresponding hook formations for the full depth of the vertical edges of the sides. The bottom is first placed in position, next the ends are applied to the bottom, and afterwards 35 the sides are applied to both ends and bottom, all with hook engagements made by outward horizontal movement only, which is the essential feature of the invention, providing a simplified construction and enabling assembly and disassembly to be carried out easily and quickly. All hook 40 engagements, aforesaid, are secured against outward displacement, the load placed within the body assisting, but said engagements are subsequently secured by mechanical means such as clamping cleats or straps, or other means, as will be hereinafter particularly referred to.

The sides may be applied to the bottom 45 before the ends which are then applied to both sides and bottom with the same distinctive feature, hook engagements made by horizontal movement only.

The manufacturing process of forming the 50 hook joints in the component parts of the tub body is very simple and inexpensive,

while if a hook joint is damaged while the tub body is in use there is only a very short horizontal movement required to disengage the component sides, ends and bottom from each other, so that the damage 60 can be readily rectified by the use of simple hand tools.

Buffer beams are applied to the ends of the body in the well-bottomed type of tub or 65 wagon and it is preferable to construct such buffer beams in accordance with prior British Letters Patent No. 222,705.

Desirable forms of the invention are represented by the accompanying sheets of 70 drawings, Figs. 1 to 5 showing one arrangement and Figs. 6 to 8 a further arrangement.

With reference to Figs. 1 to 5:—

Fig. 1 is a longitudinal vertical broken section of the body assembled. 75

Fig. 2 is a plan of Fig. 1.

Fig. 3 is a similar plan but with the parts disassembled.

Fig. 4 shows in vertical section the bottom and two ends disassembled. 80

Fig. 5 shows in plan two connected angle straps to secure the hook engagements.

The body of the tub or wagon is built up of separately constructed bottom *a*, separately constructed sides *c* and *d*, and separately 25 constructed ends *e* and *f*. The bottom *a* is flat, and its boundary edge is turned upwardly and inwardly to form all round said bottom an upper hook edge *a*² of substantially **U** cross-sectional shape, the corners being divided or slotted, at *a*³, in the web of the hook for convenience. The lower horizontal edge and the vertical edges of each side *c* and *d*, and each end *e* and *f*, are shaped into hook 30 cross-sections. Each end has inturned vertical edge hooks *g*, *g*², of **U** cross-section, and its lower and horizontal edge is turned inwardly and then outwardly into an outwardly opening hook *g*³ of **U** cross-section. Each side has its vertical edge first turned inwardly and then outwardly into a hook *g*⁴ of **U** cross-section, 35 the same as the hooks *g*², the specific shaping of the hooks being dependent upon whether the ends *e* and *f* are applied to the bottom *a* prior to the sides, or the sides applied prior to the ends. It will be clear 40 from the drawings that the hooks of the adjacent vertical edges of the sides and ends correspond, and that the hooks of the lower

horizontal edges of the sides and ends correspond to the hook edges a^2 of the bottom a . On building up the body the bottom a is first put into position, and then the opposite ends e and f are made to engage the bottom, after which the opposite sides c and d are made to engage the bottom and both the ends, all engagements by horizontal movement only outwardly and immediately and wholly.

There is therefore an inter-locking engagement of all the hooks which the load in the tub or wagon always tends to maintain, but such engagements are mechanically secured by the application of cleats or clamping straps which lie over or against the hook joints to hold them securely in engagement and are bolted to the sides, ends and bottom.

The engagements aforesaid are mechanically held by various devices. In Figs. 1 and 2 h are the heads of bolts applied to the bottom a to hold the hook engagements at the corners behind the backs of the hooks, while i are angle straps holding the engagements high up by riveting and bolting to the sides and ends and fitting against the hook engagements by shapings, while j are corner cleats applied low down to overlie the hook engagements and be bolted to the bottom a . Fig. 5 shows how two angle straps may be connected by a bar, i^2 secured to one of the sides to become a permanent part thereof.

From the foregoing it will be clear that the bottom ends and sides can be very quickly and most effectively assembled and disassembled, the latter of particular advantage in the case of accident in a mine when tubs frequently have to be entirely taken to pieces to clear a roadway.

It will also be obvious that the hook formations according to the invention are convenient for production, having in view the particular horizontal engagements by which they are put together.

Figs. 6 to 8 show a form of invention aforesaid carried out in a well-bottomed tub.

Fig. 6 is a plan of the bottom with a buffer beam applied.

Fig. 7 is a perspective view of a portion showing the bottom, a side and an end, and a buffer beam engaging.

Fig. 8 is a perspective view of a portion of the bottom only.

Said bottom a is formed with the usual well a^3 , but across the well the hook edges a^2 at the boundary are cut away, as clearly shown by Fig. 8.

Said bottom is longitudinally slotted at a^4 at the summit of the vertical wall a^5 of the well, to receive the horizontal end wall a^2 of a buffer beam x , constructed in accordance with prior British Letters Patent No. 222,705.

Portions of a side c and an end f are shown engaging each other and the bottom

a in manner aforesaid, with reference to Figs. 1 to 4, but it will be clear from the drawings of this arrangement that the hook edge g^3 of the end also engages the upper horizontal flanges x^3 of the buffer beam, and is cut away at y to accommodate the upper horizontal flange x^4 of the buffer beam end, said buffer beam being strongly riveted to the vertical walls of the well, at x^5 by the assistance of a U shaped plate x^6 , and abutting against the end edges of the well, as represented at x^7 .

The buffer beam is a hollow structure as clearly represented in Figs. 6 and 7, and its heads x^8 contain buffer blocks applied in accordance with the patent cited.

The form of the invention Figs. 6 to 8 is incorporated to show how the invention Figs. 1 to 4 can be applied to a well-bottomed tub, and how the buffer beam of the prior patent is applied to this form of the invention.

Having now described our invention and in what manner the same is to be performed, we declare that what we claim is—

1. A pit-tub, wagon or like body combining a bottom having boundary edge hook formations turned inwardly, opposite sides having vertical edge and lower horizontal edge hook formations, opposite ends having vertical edge and lower horizontal edge hook formations, the vertical edge hook formations of the sides and ends to correspond, and the horizontal edge hook formations to correspond to the boundary edge hook formations of the bottom, the whole of the hook formations being put into engagement by horizontal movement outwardly of the sides and ends, and devices for subsequently securing said engagements, substantially as described.

2. A pit-tub, wagon or like body combining a bottom having boundary side and end edges turned inwardly, opposite sides having vertical edge and lower horizontal edge hook formations turned inwardly and then outwardly, opposite ends having vertical inwardly turned edge hook formations and lower horizontal edge inwardly and outwardly turned hook formations, the vertical edge hook formations of the sides and ends to engage, and the horizontal edge hook formations to engage the boundary edge hook formations of the bottom, the whole of the hook formations being put into engagement by horizontal movement outwardly of the sides and ends in relation to the bottom, and upper and lower mechanical devices for securing the engagements of the sides and ends to each other and to the bottom, substantially as described.

3. A pit-tub, wagon or like body combining a bottom having boundary edge hook formations turned inwardly and a central well formation, the buffer beam secured to

the bottom at each end of the well formation, opposite sides having vertical edge and lower horizontal edge hook formations, opposite ends having vertical edge and lower horizontal edge hook formations, the vertical edge hook formations of the sides and ends to correspond, and the horizontal edge hook formations to correspond to the boundary edge formations of the bottom, the whole of 10 the hook formations being put into engage-

ment with each other and with the buffer beams by horizontal movement outwardly of the sides and ends, and devices for subsequently securing said engagements, substantially as described.

In testimony whereof we have signed our names to this specification.

ALBERT WEDDELL.

WILLIAM THOMAS TOLHURST.
